J. H. BRADDON.
AUTOMATIC VALVE FOR GAS STOVES,
APPLICATION FILED NOV. 10, 1914.

Patented May 2, 1916.

UNITED STATES PATENT OFFICE.

JAMES H. BRADDON, OF LORAIN, OHIO.

AUTOMATIC VALVE FOR GAS-STOVES.

1,181,830.

Specification of Letters Patent.

Patented May 2, 1916.

Application filed November 10, 1914. Serial No. 871,319.

To all whom it may concern:

Be it known that I, JAMES H. BRADDON, a citizen of the United States, residing at Lorain, in the county of Lorain and State of Ohio, have invented a new and useful Automatic Valve for Gas-Stoves, of which the following is a specification.

This invention has reference to automatic valves for gas stoves, and its object is to provide a valve for controlling the gas supplied to the burner or burners of a gas stove which will supply the burner with gas only in the event that a cooking utensil or the like is in position over the burner.

The invention comprises a valve structure between the main supply pipe and each burner or group of burners, provided with a main cut-off valve and another cut-off valve having a normal tendency toward the closed position and movable to the open position by the proper article placed over the burner. The valve structure is also provided with a pilot flame device having means for its control and wholly out of control of the automatic valve.

Provision is made for adjusting the valve structure and especially that part responsive to the cooking utensil to different positions to one side or the other of the center line of the valve structure, so as to accommodate the valve structure to different types of burners.

The invention also includes other features which will be explained farther on.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings:—Figure 1 is an elevation of the improved burner structure as applied to a stove with the main gas supply pipe and a part of the frame of the stove in cross-section, only so much of the stove being shown as is necessary for an understanding of the invention. Fig. 2 is a plan view of the structure shown in Fig. 1, showing the main gas supply pipe in plan and omitting that portion of the frame of the

stove shown in Fig. 1. Fig. 3 is a section on the line 3—3 of Fig. 2 with some parts shown in Fig. 2 omitted. Fig. 4 is a section on the line 4—4 of Fig. 2, some distant parts being omitted. Fig. 5 is a section on the line 5—5 of Fig. 3. Fig. 6 is a section on the line 6—6 of Fig. 3. Fig. 7 is a fragmentary elevation showing some of the parts disclosed in Fig. 1 and illustrating an adaptation of the invention.

Referring to the drawings there is shown a burner 1 and a small portion of the cover frame 2 of a gas stove, and there is also shown a portion of the main gas supply pipe 3 of the stove. These parts, which are all that it is necessary to show for an understanding of the invention, may be taken as indicative of a gas stove of any approved or improved type.

The burner 1 is provided with a neck 4 and between this neck 4 and the pipe 3 the valve structure of the present invention is installed. There is provided a body member 5 having a side nipple 6 threaded to enter the pipe 3, as in Figs. 1, 2 and 3, or to enter an elbow 7 applied to the pipe 3, as in Fig. 7, since in some forms of gas stoves it is customary to connect up the burners 1 with the supply pipe 3 at a lower level than in other forms of gas stove. The nipple 6 has a bore or longitudinal passage 8 leading to a port 9 formed in a valve plug 10 mounted in the body 5 for oscillatory movement. The plug 10 is made of the customary taper type, and is held to its seat by a spring 11 applied about an adjusting screw 12 at the small end of the plug. The other or large end of the plug has an angle handle or lever 13 thereon. This lever, which constitutes the manipulating lever of the plug, may be cast in one piece therewith or otherwise applied, and has a manipulating end 14 offset to one side of the axis of the plug 10.

In the installed position of the valve structure the axis of the plug 10 is usually horizontal and the manipulating end 14 of the handle 13 is about upright when the valve plug 10 has its port 9 in what may be termed the open position. In the closed position of the valve plug 10 the manipulating end 14 extends at an angle to both the vertical and horizontal, the valve plug 10 having a movement of rotation about its axis sufficient to carry the port 9 into and out of communication with the passage 8, and the

extent of this movement is controlled by a pin 15 on the body of the valve plug moving in an elongated notch or recess 16 in the body 5 of the valve structure. The purpose of offsetting the valve plug handle 13 is to accommodate the structure to different means of connection with the pipe 3 and more particularly to accommodate the structure for connection to the pipe 3 through the elbow 7. If the handle 13 were radial throughout its length and had no angle manipulating end 14, the amount of movement provided for the opening and closing of the valve with the handle 14 upright in the open position, would cause the handle to strike the pipe 3 before the valve plug had reached the fully closed position. By offsetting the handle as shown and described, the pipe 3 does not interfere with the proper manipulation of the valve plug.

The valve body 5 is provided with a bonnet 17 having at one end a threaded portion 18 adapted to screw into the body 5 and thereby form a chamber 19 therein. Within this chamber, and constituting the bottom thereof in the installed position of the valve structure, is a ledge 20 having a valve seat 21 therein communicating by a passage 22 with the bore or seat provided for the valve plug 10. In the particular construction shown, where the nipple 6 is substantially horizontal in the installed position of the device, the passage 8 is also horizontal, while the passage 22 is upright or vertical. Consequently the port or passage 9 through the valve plug 10 is an angle passage, so that when in communication with the passage 8 it also communicates with the passage 22 despite the angular relation of these passages one to the other.

Carried by the bonnet 17 is a valve stem 23 axial to the bonnet and terminating at the lower end in a valve head 24 adapted to the seat 21. A spring 25 encircling the stem 23 between the bonnet 17 and the valve head 24 tends constantly to hold the valve head 24 in the closed position.

That end of the bonnet remote from the interior of the valve is axially counterbored and threaded to receive a packing gland 26 retaining packing 27 in the counterbore about the valve stem 23. The exterior of the bonnet about the counterbore is threaded and also formed with a radial shoulder 28 to which is applied a ring-shaped bracket 29 held to the shoulder 28 by a nut 30 applied to the threaded exterior of the counterbored end of the bonnet. The bracket is formed with an upstanding arm 31 bifurcated at the upper end and there formed into a pair of opposed ears 32 carrying a pivot pin or bolt 33. The valve stem 23 is of sufficient length to extend for an appropriate distance beyond the gland 26 and there receives a collar 34 held in any desired position of ad-

justment along the stem by a set screw 35 or in any other appropriate manner.

The pivot pin 33 traverses a lever 36 and constitutes the pivot or fulcrum therefor. This lever 36 has a short arm 37 terminating in a yoke 38 with rounded terminal portions 39 straddling the valve stem 23 and underriding the collar 34. The lever has a long arm 40 with a drop portion 41 and terminates in a sleeve 42 having its bore perpendicular to the length of the lever and entered by a set screw 43 carried by the lever. The drop portion 41 is designed to locate the free end of the longer arm of the lever at a lower level than the shorter arm to provide for differences in elevation of parts of the gas stove. Entering the sleeve 42 is an angle end 44 of a rod 45 having the end remote from the angle end 44 bent at an angle to the main portion of the rod, as shown at 46, the bent or angle ends 44 and 46 extending from the main portion of the rod in opposite directions. The end 46 terminates in a knob or button 47.

When the parts are in operative position the knob 47 is in overstanding relation to the burner 1 and is at a higher level than the top 2 of the stove. If, now, any article of sufficient weight be placed upon the knob 47 it is depressed causing the lever 36 to turn upon its fulcrum 33, so that the ends 39 of the arm 37 lift the valve stem 23 through the collar 34, thereby compressing the spring 25 and lifting the valve head 24 out of the seat 21. If under these circumstances it be assumed that there is a supply of gas under pressure in the pipe 3, such gas finds its way through the passage 8, port 9 of the valve plug 10, and passage 22 into the chamber 19. This chamber is in constant communication with a passage 48 extending lengthwise through a neck 49 formed on the body 5 diametrically opposite from the nipple 6. The passage 48 opens into the burner neck 4 through certain regulating means to be described, and consequently when the valve 21 is opened gas flows with such freedom as is provided for by the regulating means, to the burner 1, where it is ignited in a manner to be described, and the burning gas supplies heat in the usual way, but only so long as the cooking utensil or other article to be heated is in engagement with the knob 47 to thereby cause the opening of the valve 21. As soon as the article being heated is removed from the stove, the spring 25 is free to act and at once causes the closing of the valve and the cutting off of the gas supply to the burner 1.

In order to initially regulate the supply of gas flowing to the burner when the valve head 21 is in the open position, the passage or bore 48 is counterbored at its outer end, as shown at 50, and is also there internally threaded. Lodged in this counterbore is a

needle valve stem 51 terminating at one end in a needle valve 52 and at the other end in an expanded head 53 formed with through passages 54 and always maintaining its position at the bottom of the counterbore. This position however does not interfere with a maximum supply of gas from the passage 48 into the counterbore 50. Entering the threaded outer end of the counterbore 50 is a screw plug 55 having the outer end closed except for a central passage 56, and this plug is provided with an interior bore 57 freely open at the inner end and communicating with the passage 56. The plug 55 bears against one end of a spring 58 lodged within the counterbore 50 and bearing against the head 53 so as to always maintain this head at the inner end of the counterbore with such force as the compression of the spring may exert. By screwing the plug 55 into or out of the counterbore to an appropriate extent the passage 56 is more or less throttled by the needle valve 52 so that the effective size of the outlet for the gas from the valve structure into the neck 4 of the burner may be predetermined by a suitable adjustment of the plug 55. The pressure exerted by the spring 58 is of no material moment, since it is not intended that the relatively light gas pressure shall have any influence upon the needle valve, so that for all operative purposes the needle valve may be considered as stationary, but for constructive purposes it may be separately manufactured and placed in the counterbore in such manner as is shown and described, or in any other appropriate manner.

The body 5 has an offset 59 provided with a longitudinal bore or passage 60 which may be of relatively small diameter as compared with the passage 8, or this bore 60 may be as large as needed. That end of the bore 60 remote from the passage 8 is closed by a screw plug 61. The offset 59 has another bore 62 transverse to and extending across the bore 60, and this bore 62 is threaded to receive a screw plug 63 which may be employed to completely close the bore or passage 60 when such may be desirable. Between the bore 8 and the outer end of the offset 59 and on the side of the bore 62 remote from the bore or passage 8 is another passage 64 which may be of quite small diameter and is counterbored to receive the nipple end 65 of a valve casing 66. This nipple end is provided with a longitudinal small bore 67 opening into a larger counterbore 68 suitably internally threaded for the reception of a threaded manipulating portion 69 of a valve stem 70, which latter terminates in a needle valve 71 adapted to control the passage or bore 67. The valve casing 66 is provided with a threaded side nipple 72 opening into the counterbore 68 for receiving one end of a pipe 73 of small

diameter of a length sufficient to reach to the burner 1 and may terminate closely adjacent to the burner.

When it is desired to start the stove the valve 71 is open, and this valve controlling a passage always in communication with the pipe 23 through the respective passages 67, 64, 60 and 8, supplies gas to the pipe 73 irrespective of the position of the valve plug 10. The valve structure 66 together with the pipe 73 constitutes a pilot structure, so that a pilot flame may be provided by the pipe 73 during the time that the stove may be in use, or, in fact, such pilot flame may be in use as long as desired, since the amount of gas consumed by the pilot flame is negligible. It is customary when it is desired to use the stove to light the pilot flame before opening up the main controlling valve plug 10, or this valve plug 10 may remain open indefinitely, since the flow of gas to the burner 1 is controlled ordinarily entirely by the valve head 21. With the pilot flame going the burner 1 immediately lights up as soon as a cooking utensil or other implement is placed upon the knob 47 to depress it, so that fuel is consumed only as needed. This greatly economizes the consumption of fuel and does away entirely with the need of turning off the gas every time that the burner is not in use, or, following the more wasteful procedure, permitting the gas to burn at the burner without utilizing the heat produced thereby.

The bracket 29 may be turned about the upright longitudinal axis of the valve structure into different lateral positions, such as indicated by the dotted lines 36^a in Fig. 2, and the extent of lateral adjustment may be even greater than this. Sometimes the burner 1 is not in line with the neck 4, but is located to one side of the longitudinal center line of the neck. However, the head or knob 47 should be located somewhere near the center of the burner. The adjustability of the bracket 29, which is brought about by loosening the nut 30, makes provision for the application of the valve structure to various types of stoves without the necessity of any change whatever in the construction of the valve mechanism.

When the stove is to be left for some considerable time out of use the valve plug or cut-off valve 10 is closed and the pilot burner valve plug or cut-off valve is closed, the automatic valve plug 24 requiring no manipulation to cut off the gas, since it has a normal constraint to the cut off position and moves thereto on the removal of the cooking utensil or other article that had been placed over the burner.

When the stove is in use the pilot burner cut-off valve is opened and the pilot burner

- is lighted, but because of the minute quantity of gas so used, which quantity is often times insufficient to make any perceptible show upon the gas meter, the pilot flame 5 may be lighted, say, in the morning and kept lighted throughout the day, and the cut-off valve 10 may be opened and allowed to remain open throughout the day, whereupon after once lighting the pilot flame no 10 further attention is needed, since the act of placing the cooking or other utensil upon the stove over the burner in engagement with the button 47 and removing it therefrom is sufficient to light up the burner and put it out respectively.
- It is advantageous to have the cut-off valve 10 under the control of a manipulating handle which stands upright when in the open position, since then any disturbance of this handle will cause the shutting off of the gas and disturbances to which the handle may be subjected are far more liable to move it downwardly than upwardly. Accidental opening of the valve 20 plug 10 under circumstances which might possibly permit the escape of gas at the burner at times when the pilot burner is not lighted, but is entirely cut off, is not liable to happen.
- 30 What is claimed is:—
1. An automatic valve structure for gas stoves comprising a unitary valve casing with an inlet nipple on one side and an outlet neck on the other side, and both located at a low point of the casing in the installed 35 position of the valve, a manually operable cut-off valve in the casing between the nipple and neck and located at a low point in the casing to turn upon a substantially horizontal axis, an automatically closing valve in the casing between the first-named valve and the outlet neck and movable up and down in a direction substantially perpendicular to the axis of movement of the first-named valve, said second-named valve being provided with opening means connected thereto above the casing and of a length to override a gas burner of the stove to which the valve structure is to be applied, and a pilot burner and valve therefor having a gas connection to the inlet gas nipple 40 on the nipple side of the first-named valve.
  2. An automatic valve structure for gas stoves having an automatic valve for controlling the passage of gas therethrough, a

lever for actuating the automatic valve and of a length to be engaged by an article placed over the burner of the gas stove to which the valve structure is applied, and a supporting bracket for the lever mounted on the valve structure and movable about an axis coincident with the line of movement of the automatic valve.

3. An automatic valve structure for gas stoves, comprising a body member, a bonnet thereon, a valve carried by the bonnet and having a normal constraint toward the closed position, said valve controlling the passage of gas through the valve structure and provided with a stem mounted in and movable axially through the bonnet, an adjustable collar mounted on the stem, a support carried by the valve structure and movable about the axis of the stem, and a lever carried by said support and engaging the collar and having means adapted to be engaged by an article placed over the burner of the stove on which the valve is installed.

4. An automatic valve structure for gas stoves having an automatic valve with a normal constraint toward the closed position, operating means for the valve for moving it to the open position and adapted to be actuated by an article placed over the burner of the stove when the valve is in the installed position, and a support for the operating means carried by the valve structure and movable with relation to the automatic valve to locate the operating means in different angular relations to the valve structure, whereby the valve structure is adaptable to stove burners of different types.

5. An automatic valve structure for gas stoves comprising a body member, a bonnet thereon, a valve mounted in the bonnet for movement therethrough and having a normal constraint toward the closed position, a lever for moving the valve toward the open position, and a supporting bracket for the lever mounted on the bonnet and movable to different positions about the longitudinal axis of the automatic valve.

In testimony, that I claim the foregoing as my own, I have hereto affixed my signature in the presence of two witnesses.
